UNITED STATES PATENT OFFICE.

SAMUEL J. TURNER, OF CHICAGO, ILLINOIS.

DESIGN FOR A CORNER-POST FOR BEDSTEADS.

SPECIFICATION forming part of Design No. 30,343, dated March 14, 1899.

Application filed January 21, 1899. Serial No. 702,992. Term of patent 7 years.

To all whom it may concern:

Be it known that I, SAMUEL J. TURNER, a citizen of the United States of America, residing at Chicago, in the county of Cook and State of Illinois, have invented a certain new and original Design for Corner-Posts for Bedsteads, of which the following is a specification.

My invention relates to a new and original design for corner-posts for bedsteads, of which the following is a specification, the design being shown by means of the accompanying drawings, of which—

Figure 1 is an edge elevation in said design, 15 and Fig. 2 a side elevation thereof.

Referring to the figures, A is the main portion of the post, which is flat, the upper part

a and the lower part a' being approximately straight and being separated by a laterally-curved portion a².

The characteristic features of this design are comprised in a bed-post having the flat portion A comparatively straight at its upper and lower parts and provided with the laterally-curved part a².

I claim as new and desire to secure by Letters Patent—

The design for a corner-post for bedsteads, as herein shown and described.

SAMUEL J. TURNER.
